UNITED STATES PATENT OFFICE.

JOHANN BALDINGER, OF AMBONI-ESTATE, EAST AFRICA.

METHOD AND MACHINE FOR CLEANING AND POLISHING FIBERS.

Application filed April 7, 1925. Serial No. 21,448.

This invention relates to improvements in or relating to cleaning and polishing fibers obtained from the leaves of agaves and other fibrous plants, and more particularly to improvements in the known method of treating the scutched and dried fibers which consists in gripping them at their middle portions by a conveyor chain, belt or the like and conducting them with a change of gripping point between pairs of cleaning drums which are provided with cleaning devices such as combs, teeth, rakes, brushes, or the like, and operate upon the bundle of fibers from the gripping point toward the ends of the bundles. In the known cleaning processes of this art the same side of the fiber bundles is operated upon at each cleaning station, so that the cleaning of the fibers is incomplete.

The object of the invention is to provide improvements in the method of and means for carrying out these cleaning and polishing processes.

According to the present invention the fiber bundles are so conducted through the cleaning stations that at each station a different surface of the fiber bundles is presented to the cleaning devices. That is to say during a continuous procedure different surfaces of the fiber bundles or bundle ends are operated upon. In this way the cleaning process is considerably improved. This manner of operation upon the fiber bundles is carried out, for example, by automatically turning over the fiber bundles between the first and second cleaning stations at which the bundles are cleaned downwardly.

An embodiment of the invention is shown, by way of example, on the accompanying drawing, in which

Figs. 1 and 2 show the cleaning means respectively in elevation and in plan view,

Fig. 3 shows a cleaning knife in combination with the entrance and outlet of the drum,

Fig. 4 is a diagrammatic view of the cleaning machine seen from the entrance side and shows especially the first pair of cleaning drums which in this case have eight cleaning knives instead of four as in Figs. 1 and 2,

Fig. 5 is a diagrammatic view similar to Fig. 4 showing the pair of cleaning drums with divided shoe and conveying disk between the two parts of the shoe,

Fig. 6 illustrates the cleaning process on the first pair of cleaning drums shown in Fig. 4,

Fig. 7 illustrates the cleaning process on the second pair of cleaning drums shown in Fig. 5, and

Fig. 8 is an elevation of the second set of cleaning drums taken in the direction of the arrow at the right of Fig. 1.

As the fibers never come out of the flesh stripping machine perfectly clean, some particles of leaf flesh adhering always to the fibers, and as after the drying they are of dull color, they must be cleaned and polished. This has hitherto been done mainly by hand in such a manner that the fibers, packed in bundles were fed to a cleaning drum, the cleaning devices of which, made from piassava fiber or from metal wire, cleaned the one end of the bundle whereupon the bundle was turned and the other end subjected to the cleaning. This work is dangerous for the persons who carry it out.

In the cleaning machine shown in Figs. 1 to 8 the conveyor (chain, rope or the like) is designated by 7. 8 is the feeding disk for the first pair of cleaning drums 9, 10. Between the two cleaning drums 9 and 10 the common double shoe 11 is arranged as shown in Fig. 4. For the second pair of cleaning drums 14 and 15 the feeding disk 13 projects from below through the double shoe 11 as shown in Fig. 5. Between the two pairs of cleaning drums the reversing roller system 12 is arranged which serves to clamp another point of the fibers adjacent to the point which has been clamped at the first pair of cleaning drums so that the part of the fiber fleece which owing to the previous clamping has remained uncleared is made accessible for the cleaning in the next following pair of cleaning drums. The cleaning drums are provided with cleaning knives 16.

Figs. 6 and 7 show clearly how it is possible to preserve the cleaning direction from above to below at both pairs of cleaning drums, the fiber fleece being nevertheless cleaned thoroughly on both sides.

According to Fig. 6 the common conveying band 7 moves into the plane of the illustration and draws along accordingly the fiber fleece clamped at the middle. The fiber fleece is therefore cleaned from the middle toward both ends by a stroke of the knives in a downward direction. The fiber material traveling around the feeding disk 13 is turned, coming from below, so that its lower side is turned upwards and gets in the position shown in Fig. 7 hanging down from above between the

conveyor 7 and the feeding disk 13 which projects from below through the double shoe 11. The lower side of the fiber fleece is consequently treated by the cleaning drums 14 and 15 also with a cleaning stroke directed from the top downward.

The method according to the invention presents in comparison with the commonly used cleaning method the advantage that the first pair of cleaning drums cleans the fibers from the middle towards both ends whereby, as the fibers are so to say in equilibrium under the effects of the cleaning drums, the pulling out of fibers from the clamping action of the conveying means is limited to the minimum. This advantage is preserved also in the second pair of cleaning drums, the further advantage being added that according to the new working method the layer of fiber is turned upside down before it is exposed again to the action of another pair of cleaning drums, the side of the layer of fibers which had been turned towards the shoe being now submitted to the action of the cleaning knives, wherefrom results as much more perfect treatment than has been obtainable according to the hitherto used working methods.

The knives 16 are further, according to the invention, of an improved shape. As can be seen from Fig. 3 the part 18-19 serves for smoothing the layer of fibers whereupon between 19 to 20 teeth are arranged which are at first short and blunt and then longer and more pointed so that they penetrate more deeply into the material to be cleaned, the cleaning and polishing being thus carried out very carefully. The beginning of the knife, from 21 to 18 is situated in the shield 17 in order to prevent fibers from being drawn along at 21 and wound around the axle of the drum. The part of the knife extending from 20 to 22 overlaps the right hand side shield 17 so that no fibers are pulled in at 23 and wound around the axle of the drums which could cause disturbances of working. The oblique position of the knives serves to produce an air current in the direction of conveying in the interval between cleaning drum and shoe, this air current serving to bring out of the range of the cleaning drums the free ends of the layer of fibers passing between the shoe and the drum, said free ends as far as they are not in the range of the teeth of the knives having a tendency to lag behind with regard to the middle part positively drawn along by the conveying means so that twisting of fibers could occur. The entire layer of fibers is thus laid, on the lower side and on the upper side, from the middle to the ends, parallel to the cleaning direction so that the fibers can come out parallel and without twist. For the subsequent treatment of the fibers, when they are being spun or woven into fabrics, it is advantageous that the fibers fall freely and are not twisted together.

Having described my invention, I claim:

1. In a device for cleaning fibers, two pairs of cleaning drums having fiber cleaning means, a conveying disk associated with each pair of cleaning drums, one pair being arranged below the axis of its associated disk, the other pair being arranged above the axis of its associated disk, and a conveyor running under said first mentioned disk, thence under and substantially half way around said second mentioned disk, the construction being such that bundles of fibers are adapted to be moved by said conveyor under said first mentioned disk and between the associated cleaning drums, whereby the free ends of the bundles are cleaned on one side, the bundles then being carried by said conveyor under said second mentioned disk and substantially half way around the same to the top thereof, whereby said bundles are turned over and the other side of the free ends of the same cleaned by the second set of cleaning drums.

2. A device for cleaning fibers in accordance with claim 1 in which the portion of the conveyor which carries the fiber bundles through the two cleaning stations is crossed by the empty returning portion of the conveyor so that the conveyor traverses a substantially ∞ shaped course.

3. In a machine for cleaning fibers comprising a rotating cleaning drum and means for conveying bundles of fibers past said drum in position to be cleaned thereby, outstanding cleaning knives on said drum having fiber engaging teeth, the teeth at the ends of the knives which first engage the fibers being short and blunt, the teeth increasing in length and sharpness toward the other ends of the knives.

4. In a machine for cleaning fibers comprising a rotating cleaning drum and means for conveying bundles of fibers past said drum in position to be cleaned thereby, cleaning knives on said drum, and a shield at each side of said drum, the shield at the entering side of said drum having an extension covering one end of said knives, said knives having extensions on their opposite ends projecting over the other shield.

5. Process of cleaning fibers by means of pairs of drums having cleaning devices, which consists in grasping a bundle of fibers substantially at its mid-point, conveying said bundle between one pair of drums, whereby the two free ends of said bundle are simultaneously cleaned on one side thereof, grasping the bundle at a different point closely adjacent its mid-point, turning the bundle over, and conveying the bundle between another pair of drums, whereby the two free ends of said bundle are simultaneously cleaned on the other side thereof.

6. Process of cleaning fibers by means of pairs of drums having cleaning devices, which consists in grasping a bundle of fibers

substantially at its mid-point, conveying said bundle between one pair of drums and simultaneously cleaning the two free ends of said bundle downwardly with said cleaning device, grasping said bundle at a different point closely adjacent its mid-point, turning said bundle over, conveying said bundle between another pair of drums, and simultaneously cleaning the other side of the free ends of said bundle downwardly with the cleaning devices of said second pair of drums.

7. In a fiber cleaning machine the combination with two pairs of cleaning drums of means for conveying bundles of fibers between said pairs of drums and turning said bundles

over during their passage from one pair of drums to the other comprising a conveying disk having its lowermost point substantially on the line of centers of the first pair of drums, a second conveying disk having its uppermost point substantially on the line of centers of the second pair of drums, and an endless conveyor having a bundle receiving portion running toward said first mentioned disk and a bundle conveying portion passing under said two disks and substantially halfway around the second disk. 20 25

In testimony whereof I affix my signature.

JOHANN BALDINGER.
